UNITED STATES PATENT OFFICE

HAROLD T. GRISWOLD, OF EVANSTON, ILLINOIS, ASSIGNOR TO SANFORD MANUFACTURING CO., OF CHICAGO, ILLINOIS, A CORPORATION OF ILLINOIS

DESIGN FOR A BOTTLE CLOSURE

Application filed May 7, 1931. Serial No. 39,746. Term of patent 3½ years.

To all whom it may concern:

Be it known that I, HAROLD T. GRISWOLD, a citizen of the United States, residing at Evanston, Cook County, Illinois, have invented a new, original, and ornamental Design for a Bottle Closure, of which the following is a specification, reference being had to the accompanying drawing, forming a part thereof, showing my new design.

The figure is a perspective view of a bottle closure embodying my present invention.

I claim:

The ornamental design for a bottle closure as shown.

HAROLD T. GRISWOLD.
